UNITED STATES PATENT OFFICE.

WALTER C. BRÖCKER, OF ITZEHOE, GERMANY.

MACHINE FOR KNOTTING NETS.

Application filed August 30, 1921. Serial No. 497,074.

To all whom it may concern:

Be it known that I, WALTER C. BRÖCKER, residing at Itzehoe, Brookhafen, Germany, have invented certain new and useful Im-
5 provements in and Relating to a Machine for Knotting Nets, of which the following is a specification.

This invention relates to a machine for making knots and particularly to a machine 10 for producing nets from series of threads, the one series or warp threads being moved or guided by needles while the other series are actuated by means of shuttles.

One feature of the invention consists in 15 arranging the shuttles so that their openings, from which the shuttle threads issue, lie near the point where the knots are made and swing to and fro around the knotting points. The center of the arc described by the oscillating shuttles preferably lies near the knotting point.

Another feature of the invention consists in imparting to the shuttles, in addition to the primary oscillating motion already de- 25 scribed, a secondary motion by which the opening from which a shuttle thread issues is moved away from the knotting point at the moment in which the shuttle commences to execute its backward swinging motion. 30 This may be accomplished by arranging the shuttles to be moved in a rocker arm adapted to swing around an axis or pivot lying adjacent the knotting point, and by pivotally attaching the shuttle support to this 35 arm, and arranging the shuttle support to swing around its pivot in the rocker arm by means of a crank or the like.

Another object of the invention is to avoid the unsymmetrical meshes produced by previously known net-making machines and to provide a simple arrangement for producing symmetrical meshes. The means by which this is accomplished in accordance with the invention consists of turnable 45 hooks which, after seizing the shuttle threads, are turned so as to form loops in them. These looping hooks are arranged to turn alternately to the right and left, and the arrangement of the working parts of the 50 machine is such that the knots are formed at the points of the hooks. By this means the spots where the knots are formed are shifted alternately to opposite sides of a middle line. The warp threads are shifted 55 in a corresponding manner to the left and right of the middle line by their needles. In

accordance with the invention the alternate lateral displacements of the warp threads during the up and down motions of the needles is effected automatically. 60

The invention is shown in the drawing in which:

Fig. 1 is a side view, partly in section, of the parts of the machine whose illustration is necessary for a comprehension of the operation of the moving parts of the machine. 65

Fig. 1^a is a front view, partly in section, of a part of the machine.

Figs. 2 and 3 illustrate the manner in 70 which the knots are formed.

Figs. 4 to 8 illustrate the motions of a shuttle, the corresponding looping hook and needle during one complete oscillation or to and fro movement of a shuttle.

Fig. 9 illustrates the symmetrical meshes 75 formed with the aid of the looping hooks according to this invention.

Fig. 10 shows the looping hooks in two different positions.

Fig. 11 is a front view showing the needle 80 carrier.

Fig. 12 is a side view of Fig. 11.

Fig. 13 is a top view of Fig. 11.

Referring to Fig. 1, it will be seen that the warp threads *a* pass over a drum or roller *c* 85 to needles *d*. The woof threads *b* issue from circular enclosed bobbins *f* supported in shuttles *g*. Knots are formed with the warp and woof threads at points *e*, hereinafter called knotting points. The shuttles *g* lie 90 against thin disks *h* connected to each other by a link member which is hook-shaped at its two ends and is attached to a U-shaped support *h'*.

The support *h'* bears the holding disks *h* of all of the shuttles in a row 95 or group. The support *h'* is fixed to an end plate *h²* which is arranged to turn on a pivot *m* journalled in a lever *q*.

The lever *q* is also arranged to turn on a pivot *n* located near the knotting point *e*. The short arm *q'* of the lever *q* is linked to a connecting rod *o²* to which reciprocating motion is imparted by an eccentric *o'* rotated by a shaft *o*. The end plate *h²* is linked to a connecting rod *n²* 100 which is reciprocated by an eccentric *n'* rotated round the pivot *n*. The finished net produced by the machine is delivered by delivery rollers *l* or the like.

Arranged near the knotting points is a 105 row of hooks *k* which are adapted to seize the shuttle threads and to then execute a turning motion for the purpose of forming

loops in the threads. The looping hooks are formed as shown in Fig. 10 so that when they are turned to the right the positions of their points differ from the positions which they occupy when the hooks are turned to the left. The knots are formed at the points of the hooks *k*.

The manner in which the knots are formed is illustrated in detail in Figs. 2 and 3. 10 After a hook *k* has seized a shuttle thread *b*, and then executed a turn so as to form a loop as shown in Fig. 2, a needle *d* carries a warp thread *a* through the loop in the thread *b*. Then the shuttle passes through the 15 loop formed by the needle in the thread *a* whereupon the knot is tightened as indicated in Fig. 3.

Figs. 4 to 8 illustrate the motions executed by a needle *d*, a shuttle *g* and a hook *h*. On 20 observing the motions of the eye *i* through which the shuttle thread passes out of the enclosed bobbin, it will be noted that in the positions shown in Figs. 4-6 this eye swings round the knotting point *e*. By thus arranging the eye to swing around the knotting point, the length of shuttle thread between the knotting point and the eye *i* can be much shorter than if the shuttle is moved past the knotting point in the manner 25 adopted in known machines. In Fig. 6 the shuttle is in the position in which it commences to swing backward. At this moment the eye *i* from which the shuttle thread issues receives a secondary motion by which, in 30 spite of the shuttle being bodily swung to the right as indicated by the arrows in Figs. 6 and 7, the eye *i* is moved toward the left, i.e. away from the knotting point. By this secondary motion the knot is tightened. 35 During this tightening of the knot the shuttle thread passes at a sharp angle around the corner *i'* of the eye in the bobbin holder, and in this way sufficient friction between the thread and the bobbin holder is obtained, 40 without the aid of special clamping devices, thus enabling the thread to exert the necessary pull for tightening the knot. When the said pull is exerted the hook *k* is turned into 45 the position shown in Fig. 7, from which it 50 will be observed that the knot is formed at the point of the hook.

The needles *d* as shown in Figs. 1 and 11 depend from a support *r* adapted to slide to and fro horizontally in a reciprocating slide 55 *s*. The slide *s* moves up and down between lateral vertical guides *s'*, motion being imparted to it by an eccentric rotating with the shaft *o*, Fig. 1. The needle carrier *a* has oblique end surfaces *t*, *t'*, Fig. 11, these 60 surfaces lying in the path of movable tappets *u* and *u'*, which may be brought into, and withdrawn from engagement with the end surfaces.

The tappets *u* and *u'*, as will appear from 65 Fig. 12, are linked to double arm levers *x*,

x' which can be rocked by other two arm levers *y*, *y'*, Fig. 13. The ends of the lever *y* are pivotally connected to pins *v*, *w* which are adapted to slide to and fro in holes in the left hand guide member *s'*, while the 70 ends of the lever *y'* are pivotally attached to sliding pins *v'*, *w'* in the right hand guide member *s'*. The levers *y*, *y'* are oscillated by the needle carrier *r* with the aid of the 75 sliding pins. The inner face of the needle carrier *r* has two slots *z*, *z'* which permit of the carrier *r* sliding past the protruded ends of the pins *w*, *w'* at certain times. The contrivance for shifting the needle carrier laterally to and fro operates as follows:

When the needle carrier *r* moves downward from the position shown in Figs. 12 and 13 its inner face strikes against the rounded protruding end of the pin *w'*, and thus swings the lever *y'* out of the position shown in Fig. 13, whereby the right arm of the lever *y'* swings the lever *x'* out of the position shown in Fig. 12, so that the tappet *u'* is moved until its protruding end is flush with the front surface of the right hand vertical guide member *s'*. At the same time the slot *z* at the left hand of the needle carrier *r* slides over the protruding end of the pin *w* while the protruding end of the pin *v* is pushed back by the needle carrier *r*. The receding pin *v* swings back the left hand end of the lever *y*. This again results in the tilting of the lever *x*, which shifts out the tappet *u*, so that it will engage with the end surface *t* of the needle carrier when this latter is moved upwards. The needle carrier is thus shifted to the right. At the end of its next down and up motion it will be shifted to the left by the protruding end of the tappet *u'* and so forth.

I claim—

1. In a knot-making machine for knotting together series of threads, means for producing knots at a certain knotting point, said means comprising a shuttle with an exit for one of the said threads, means for imparting a primary arcuate motion to the shuttle around the knotting point, and means for imparting a secondary motion to the said shuttle whereby a secondary motion is imparted to the said exit.

2. In a knot-making machine for knotting together series of threads, means for producing knots at a certain knotting point, said means comprising a shuttle with an exit for one of the said threads, means for imparting a primary oscillating arcuate motion to the shuttle around the knotting point, and means for imparting a secondary motion to the said shuttle at a moment when the arcuate motion of the shuttle is reversed after the formation of a loose knot.

3. In a knot-making machine for knotting together series of threads, means for producing knots at a certain knotting point,

5 said means comprising a rocker arm with its pivot close to the knotting point, a shuttle with an exit for the thread therein, a shuttle-carrier pivotally mounted on the rocker arm, means for rocking the rocker arm, and means for turning the shuttle-carrier whereby the exit of the shuttle is moved away from the knotting point at the moment when the movement of the rocker is reversed after 10 the formation of a loose knot.

15 4. In a knot-making machine for knotting together series of threads, means for producing knots at a certain knotting point, said means comprising a shuttle with an exit for one of the said threads, a rocker arm with a pivot close to the knotting point, a shuttle-carrier pivotally mounted on the said rocker arm, a reciprocating rod for oscillating the rocker arm, and a second reciprocating rod 20 for moving the exit of the shuttle in the shuttle carrier away from the knotting point at a moment when the movement of the rocker arm is reversed after the formation of a loose knot.

25 5. In a knot-making machine for knotting together series of threads, means for producing knots at a certain point, said means comprising a shuttle with an exit for one of the said threads, a rocker arm with a pivot close to the knotting point, a shuttle carrier pivotally mounted on the said rocker arm, a reciprocating rod for oscillating the rocker arm, a second reciprocating rod for moving the exit of the shuttle in the shuttle carrier 30 away from the knotting point at a moment when the movement of the rocker arm is reversed after the formation of a loose knot, and a revolving member for operating the said second reciprocating rod the pivot of 35 the revolving member coinciding with the pivot of the rocker arm.

40 6. In a knot-making machine for knotting together series of threads, means for producing knots at a certain knotting point, said means comprising a thread feeding needle adapted to move one of the said threads, a 45 needle carrier, means for reciprocating the needle with its carrier, movable engaging

members for engaging the needle carrier, and surfaces which engage with the said 50 engaging members made to produce transverse motion of the needle carrier when they engage with the engaging member.

7. In a knot-making machine for knotting together series of threads, means for producing knots at a certain knotting point, said means comprising a needle, a needle carrier, means for reciprocating the needle with its carrier, a turnable hook, and means for turning the point of the hook to opposite 55 sides of the said needle, the direction of travel of the point of the hook being the opposite of that of the needle-carrier.

15 8. In a net knotting machine, two series of means for supplying threads, other means 60 for knotting together the threads supplied by the two series, and a series of hooks each hook being adapted to be turned round its axis into two different positions to cooperate in both positions with a thread of one of 70 said series, and alternately with two different threads of the other of said series, the hooks being so arranged and shaped that the threads may be held on the points of the said hooks when the knots are tightened. 75

9. In a net knotting machine, two series of means for supplying threads, a series of hooks each hook being adapted to be turned round its axis into two different positions to cooperate in both positions with a thread of 80 one of said series, and alternately with two different threads of the other of said series, and other means for knotting together the threads from the two series of means on the points of the said hooks, the hooks being so 85 arranged and shaped that the points of the hooks are displaced when the latter are turned so as to displace the knotting points of the threads.

In testimony whereof I have affixed my 90 signature in presence of two witnesses.

WALTER C. BRÖCKER.
